W. J. FYAN.
MANIFOLD HEATER FOR INTERNAL COMBUSTION ENGINES.
FILED JAN. 2, 1920.

FIG. 1.

UNITED STATES PATENT OFFICE.

WILLIAM J. FYAN, OF OLEAN, NEW YORK.

MANIFOLD HEATER FOR INTERNAL-COMBUSTION ENGINES.

Application filed January 2, 1920. Serial No. 348,884.

To all whom it may concern:

Be it known that I, WILLIAM J. FYAN, a citizen of the United States, residing at Olean, in the county of Cattaraugus and 5 State of New York, have invented certain new and useful Improvements in Manifold Heaters for Internal-Combustion Engines; and I do hereby declare the following to be 10 a full, clear, and exact description of the invention, such as will enable others skilled in the art to which it appertains to make and use the same.

This invention relates to attachments for internal combustion engines and the primary 15 object of the invention is to provide an improved means for effectively heating the intake manifold, and thereby vaporize the fuel and break the same into small particles.

Another object of the invention is to provide 20 an improved attachment for internal combustion engines which can be quickly and readily secured in place, which will effectively utilize the heat from the exhaust manifold to heat the intake manifold.

Another object of this invention is to provide 25 an attachment for internal combustion engines formed of heat conducting material which is adapted to be positioned intermediate the exhaust and intake manifold and 30 in contact therewith, so as to permit the heat from the exhaust to be utilized for heating the intake manifold.

A still further object of the invention is to provide a detachable attachment for 35 automobiles which is of heat conducting material, so constructed, that the same can be heated prior to the positioning of the same on the intake pipe of the motor, thereby facilitating the starting of the engine during cold 40 weather.

A still further object of the invention is to provide an improved device of the above character, which is durable and efficient in use, one that is simple and easy to manufacture, and one that can be placed upon the 45 market at a reasonable cost.

With these and other objects in view the invention consists in the novel construction, arrangement and formation of parts, as will 50 be hereinafter more specifically described, claimed and illustrated in the accompanying drawings, forming a part thereof in which:

Figure 1 is a side elevation of the Ford motor with the improved attachment applied thereto. 55

Figure 2 is a central vertical section taken through the device showing the same applied to a motor, and

Figure 3 is a detail perspective view of the attachment removed from the motor. 60

Figure 4 is a detail perspective view of the clamping means for the attachment, removed.

Referring to the drawings in detail, where-in similar reference characters designate corresponding parts throughout the several views, in which the numeral 1 generally indicates the improved device which is adapted to be applied to an internal combustion engine 2, which is of the ordinary Ford or 70 other preferred type. The engine 2 includes exhaust manifold 3 having the outlet pipes 4 connecting with the outlet ports of the intermediate cylinders, and the intake manifold 5. 75

An ordinary type of internal combustion engine has the intake manifold located below the exhaust manifold and in spaced relation thereto and the improved device 1 is adapted to fit and rest upon the top of the 80 intake manifold and extend upwardly therefrom into engagement with the intake pipe. The sides and the upper surfaces of the attachment are arranged to engage the exhaust manifold and the intermediate pipes 85 4 leading from the outlet ports for the intermediate cylinders.

The improved attachment 1 is preferably formed of cast iron, but it is to be understood that the same may be formed of any 90 heat conducting material and comprises a solid body 6 having a right angle extending arm 7 formed on the upper terminals thereof. The inner surface of the body 6 inclines downwardly and outwardly as at 8, 95 to conform to the configuration of the intake pipe while the sides of the arm 7 are curved inwardly as at 9 to conform to the configuration of the exhaust manifold. It will be seen that the device is so shaped to 100 snugly fit between the exhaust and intake manifold and thus becomes heated from the exhaust manifold and in turn heats the intake manifold at the turn thereof so that as the fuel is drawn up through the intake 105 pipe the same comes in contact with the hot portion of the intake manifold and becomes vaporized and broken into small particles. While the arm 7 serves to prevent turning of the attachment 1, I have provided for 110

means to clamp the attachment 1 in position and which means consists of a bar 10 which extends across the front or outer face of the solid body 6 and has one end 11 bent at a right angle and formed into a hook for engagement around one of the clamps 12 which serve to hold the intake and exhaust manifold in place. Extended through the remaining end of the bar 10 is the clamping bolt 13 which has a turned or hook end 14 for engagement around another one of the clamps 12 located at the opposite side of the solid body 6. A thumb nut 15 is threaded upon the outer face of the bar 10 at this end to cause the latter to securely clamp the attachment 1 in proper position.

From the foregoing, it will be seen that the device is so constructed that the attachment 1 may be readily placed in position and securely clamped, or released and removed, when desired. This is an important feature, as during extremely cold weather it is often necessary to provide means for heating the intake manifold prior to starting the engine. When it is desired to heat the manifold prior to starting the engine it is merely necessary to remove the device from its position and heat the same on a stove or the like and then place the same back in position. This will effectively heat the manifold and facilitate the starting of the engine.

From the foregoing description it can be seen that an improved device is provided which is of exceedingly simple and durable character, and which can be readily and

quickly fitted to Ford motors for heating the intake manifold thereof.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required, without sacrificing any of the advantages of my invention as set forth.

What is claimed as new is:

In combination with an exhaust pipe having depending portions spaced from each other, a fuel supply pipe bridging said portions, and securing clamps for one of said pipes, a heat conducting member having an extension disposed in said space and in contact with both pipes, an extension on said member in contact with one side of the fuel supply pipe, a securing bar for the member having a hook at one end integral therewith to engage one of the clamps and a hook to engage the other clamp adjustably mounted adjacent the other end of the bar.

In testimony whereof I affix my signature in presence of two witnesses.

WILLIAM J. FYAN.

Witnesses:

ROBERT E. MURRIN,
ETHEL SMITH.
